FIG-11-

INVENTOR.
WILLIAM V. ROBERTS
BY *Charles O. Bruce*
ATTORNEY.

in and in my parent application, above identified, wherein a liner, which may or may not include the resilient side wall components as integral parts thereof, has extensions thereon along the upper edges of the side wall sections, interlocking with folded over cover tabs extending from the upper edges of the container side walls. The absence of packing stresses in the container side walls, attributed to the interlocking of the resilient side wall components with the end walls, enables the container side walls to be retained in position, even under such extreme conditions, where, through rough handling during shipment, the side walls may be torn away from the end walls. The interlocking of the resilient side wall components with the end walls being independent of the side walls of the container, will enable the fruit to be retained in properly packed condition, in spite of any damage which may conceivably result to the side walls of the container during shipment, and will thus assure the safe arrival of the fruit at its destination in its originally packed condition.

The container is so designed that upon its arrival at its final destination, the contents need not be removed for display purposes, as the container itself is convertible in such a manner as to enable the contents to be properly displayed, with suitable advertising advantages inherent in the construction. When thus displayed in the container in which it has been shipped, the fruit is maintained in the same properly packed condition as during shipment, which serves to protect the same against damage which might otherwise result from the handling of such fruit in the customary manner. Inasmuch as the proper packing conditions are maintained in my improved container, by the resilient side wall components, it naturally follows that the removal of the upper layers of the fruit in the sale of the same, will not disturb the proper packing conditions of the underlayers, thus maintaining the fruit in good salable condition.

For a more detailed description of the invention, reference will now be made to the various embodiments illustrated in the drawings.

The container 1 of Figure 1 is assembled from the container blank 3 of Figure 2, the liner 5 of Figure 3, a pair of resilient side wall components 7 of the type depicted in Figure 4, and an end brace 9 for each end wall 11 as shown in Figure 1. This end brace constitutes a rectangular frame of wood or other material, into which nails may be driven, and serves as a reinforcement for and constitutes an element of each of the end walls of the container.

The blank 3 from which the container is formed is substantially rectangular in shape, and embodies a continuous longitudinal intermediate portion scored transversely at intervals, to provide alternate side and end wall sections 13, 15, 17 and 19 in sequence. The extreme end wall section 19 is provided, along its free edge, with a fastening tab 21, to be secured as by stapling to the free edge of the first side wall section 13, in the process of assembling the container. The bottom 23 of the container is formed from tabs 25, 27, 29 and 31 in sequence, extending from an edge of each of the side and end wall sections, respectively, these tabs cooperating to provide the bottom by overlapping one with the other, enabling them to be stapled together into fixed cooperating position. The end wall section 15 has extending from its opposite edge, an extension 33 marked off from the end wall section by

5 a double score line, and end wall section 19 is similarly provided with an extension 35. Each of these extensions has formed therein a row of tabs 37 along each side edge thereof and spaced from such edge a distance equal to the width of a vertical member 39 of the end brace 9.

10 The cover for the container is formed from tabs 41 and 43, each extending from the opposite edge of one side wall section, and marked off therefrom by a similar double score line. Each of such tabs 41 and 43 is divided longitudinally into two substantially equal parts 45 and 47, and 49 and 51, respectively, thus permitting each tab to be folded back upon itself, with part 45 matching up with part 47 in the tab 41, and part 49 matching up the part 51 in the other tab 43.

15 The liner blank is of rectangular form and scored transversely thereof, to provide a bottom section 53 flanked by side wall sections 55 and 57, respectively. Each of said side wall sections, 20 in turn, has an extension 59 and 61, respectively, integral therewith and marked off from its associated side wall section by a double score line. The bottom section is further scored a slight 25 distance from each longitudinal edge of the blank and parallel thereto, to create narrow tabs 63 and 65, one at each end of the bottom section 53 of the liner.

20 The container 1 utilizes a pair of the resilient 30 side wall components 7, each of which comprises a section 67 of fiberboard or the like, to which is affixed, as by stapling, a plurality of thin, resilient, wooden slats 69 or the like, which are laid parallel to the longer edge of the fiberboard 35 section, and protrude slightly beyond each end thereof. Each of the slats is of a width enabling it to force its way through an opening defined by a tab on the end wall extensions, and are spaced so as to enable these slats to align themselves with the tabs during the assembling of the container.

25 In assembling the components described, to obtain the container illustrated in Figure 1, the blank is first folded along the score lines separating the side and end wall sections 13, 15, 17 and 19, and the fastening tab 21 is secured to the free edge of the side wall 13. The bottom sections 25, 27, 29 and 31 are then turned under and overlapped, and secured in cooperating position to define the bottom of the container. The liner 5 is then fitted into position, with its bottom section 53 resting upon the floor of the container, with the side wall sections 55 and 57 matching up with the side walls 13 and 17 of the container, the width of the liner blank being approximately equal to the overall internal length of the container. The end braces are then placed in position against the end wall sections 15 and 19, and the end wall section extensions 33 and 35 are then folded over the end braces, such extensions being of such a length as to approximately reach the floor of the container, thus serving to enclose the end braces. Prior to the assembly of these end wall components, the floor section tabs 63 and 65 of the liner are raised, and following the folding over of the end wall extensions 33 and 35, the tabs 63 and 65 are permitted to spring back against these end wall extensions, thus securing the same 30 in position, as well as the end braces 9 enclosed thereby.

35 Following this, the resilient side wall components 7 are assembled in the container, with the slats 69 facing the side walls thereof. The fiberboard section 67 of each of these resilient

side wall components is of a length enabling it to snugly fit between the end wall extensions 33 and 35, and the slat extensions are preferably sufficient to approximately reach the end wall sections 15 and 19. During the assembling of these resilient side wall components, the slat ends are forced against the tabs 37, causing them to bend out of the plane of their associated end wall extension, thereby permitting the slat extensions to pass through the end wall extensions and bear against the end wall braces, whereby these resilient side wall components are locked against endwise movement in the direction of the side walls 13 and 17 of the container, and are maintained in spaced relationship thereto. The tabs 37, following the insertion of the slat extensions, bear against the slats, and maintain them in pressure engagement against the upright members 39 of the end braces. The container is completed by folding the side wall tabs 41 and 43 over the liner extensions 59 and 61, respectively, and in sealing the container for shipment, following packing of the same, the folded over side wall tabs are then brought down upon the upper edges of the end walls 11, and secured thereto. In securing the cover to the end walls, cleats are usually placed upon the folded down cover sections, prior to nailing the same to the end walls. The cover tab dimensions are preferably such as to leave a ventilating slit between the cover sections when the container is packed and made ready for shipment.

In packing a container of the type described, the fruit is packed under pressure sufficient to cause the resilient side wall components 7 to bulge outwardly in the direction of the side walls 13 and 17 of the container, whereby, in the event of shrinkage of the fruit during shipment, such shrinkage will be compensated for by the resilient side wall components, thereby maintaining the fruit in proper packed condition throughout shipment.

It will be apparent from the construction of the components and the manner of assembling the same, that none of the packing stresses will be transmitted to the side walls 13 and 17 of the container, as this is precluded by the locking engagement of the resilient side wall components 7 with the end walls 11 of the container as described. Consequently, in the event of accidental damage to the container during shipment, the contents of the container will remain in proper packed condition for shipment, and the side walls of the container will be protected against being torn away from the container proper, through the inter-engagement of the liner extensions 59 and 61 by the folded over cover tabs 41 and 43.

While in the embodiment of Figure 1, the liner 5 is disclosed as being positioned between the container side walls 13, 17, and the resilient side wall components 7, the liner may, with advantage, be inserted into the container, following the assembling of the resilient side wall components, and when this procedure is followed, the resilient side wall components will act as a support and brace for the liner, in preventing the side walls of the container from being torn away or very seriously damaged during shipment. Or the resilient side wall components may constitute the side walls of the liner.

As previously indicated, the container may be converted, upon arrival at its final destination, for advertising and display purposes. To effect such conversion, the cleats are removed, and one

5 of the cover sections, formed by the folded over tab 41, for example, and the enclosed liner extension 59, is raised to a more or less vertical position, to present to view a surface of the cover tab section 45 which may bear suitable advertising matter. In as much as the side wall liner sections occupy different planes from those in which the side walls of the container lie, any movement of a cover section from its closing position to a vertical position must necessarily result in a relative sliding movement of the liner extension within the fold of the tab. Consequently, it must necessarily follow that if such relative movement is precluded by the use of some clip or other fastening means, the cover section will remain in any angular position to which it may have been moved prior to the application of such clip. This is of advantage in the use of the box for display purposes, for the desired angular position of a cover section will depend, in large measure, on whether or not the container is tilted when placed on display.

20 The other section of the cover formed by folded tab 43 may be swung down against the side wall 17 of the container, and secured in place by nailing the same to the end braces, and this cover section may also bear suitable advertising material on the exposed surface of the tab section 49 which will thereby be presented to view. 25 In connection with this advertising aspect of my invention, it is to be noted that the exposed surfaces of the cover sections, which are to bear the advertising matter, are on the same side of the container blank, and, consequently, the desired advertising material may be printed on the blank in one operation, and this also holds true in connection with any printed matter to be placed on those other portions 41 and 51 of the cover sections which are exposed when the container is sealed for shipping.

30 In Figure 6, I have disclosed a modification of the container structure of Figure 1. The change resides in providing end wall extensions 71 without tab cut-outs, and utilizing them as portions 35 of the cover, while modifying the end wall brace construction to incorporate the features and advantages provided by the end wall extensions and end brace assembly of Figure 1. In the embodiment of Figure 6, the end wall brace comprises a rectangular frame 73 of wood or the like, over which is nailed a section 75 of fiberboard extending slightly beyond the vertical members 77 of the end brace frame. To each of these extensions, there is affixed a cleat 79, and this is adapted to be folded back into line with the adjacent vertical member 77 of the end brace frame. Tabs 81 are formed in the fiberboard section, adjacent the vertical frame members 77, in a manner corresponding to the tabs 37 provided in the turned over end wall extensions 33 and 35 of Figure 1. The resilient side wall components 7 are of similar construction to those employed in the container of Figure 1, and are assembled in like manner. The modified construction of Figure 6 offers a somewhat greater bearing surface for the ends of the resilient side wall components, due to the cleats 79 which have been added to the end wall structure. As stated in connection with the embodiment of Figure 1, the liner may be inserted following the assembly 40 of the resilient side wall components, and the same advantages will prevail as in the construction of Figure 1.

45 In the embodiment of my invention illustrated in Figure 11, the assembly has been some-

what simplified, without sacrificing any of the advantages inherent in the embodiments of Figures 1 and 6. In this embodiment, the end wall brace comprises a rectangular frame 83, to each of the vertical members 85 of which there is affixed a rib 87, and the end wall extensions 89 and 91 of the container blank 93 are narrowed down to permit such extensions to fold over the end braces when in position, and fit between these ribs. The liner blank 95 is of rectangular form and scored to provide a bottom section 97 adapted to fit between the folded over end wall extensions 89 and 91, and side wall sections 99 and 101 of corresponding length, to which are affixed slats 103 on the surface facing the side walls 13 and 17 of the container. These resilient side wall components of the liner also fit between the folded over end wall extensions, and bear against the ribs formed on the end braces, whereby they are maintained in spaced relationship with respect to the side walls 13 and 17 of the container, and are locked against endwise movement in the direction of such side walls by the ribs on the end braces. Thus, the liner 95 takes on the function formerly attributed to the resilient side wall components 7 embodied in the constructions of Figures 1 and 6. In as much as the slats 103 in the embodiment of Figure 11 do not pass through the end wall extensions, as in Figure 1, or the equivalent thereof as in Figure 6, there is no necessity for forming tabs in the end wall extensions of this embodiment, thereby not only simplifying the construction of the container, but also materially simplifying its assembly.

In the further embodiment of my invention as depicted in Figure 12, each end wall brace 105 is provided with ribs 107 or their equivalent, the internal edges of which are spaced from the frame proper, to slidably receive an end wall extension 109. After the end brace has been assembled with the end wall extension, as illustrated in Figure 12, the end wall extension may then be folded over into the container with the end brace, which, after it arrives at its final position, will enable the resilient side wall components of a liner, such as illustrated in Figure 9, to bear against the ribs 107 and be retained thereby in spaced relationship to the side walls of the container, in the same manner as in the embodiment of Figure 11.

Of course, it is apparent that in lieu of the improved liner of Figure 9, which incorporates the resilient side wall components as integral parts thereof, independent resilient side wall components of the type illustrated in the embodiments of Figures 1 and 6, may be utilized, in which case the slat extensions would not be necessary and could be eliminated.

It will be apparent from the above description of the various embodiments of my invention, that the same will fulfill all the objects of my invention. Accordingly, while I have disclosed these various embodiments in great detail, it will be apparent that the same may be subject to modification and alteration, without departing from the principles of the invention, and I, accordingly, do not desire to be limited in my protection to the details of construction illustrated and described, except as may be necessitated by the prior art and the appended claims.

I claim:

1. A container comprising end walls and outer side walls, and a resilient inner side wall component having spaced slats attached thereto, with the ends of said slats projecting at each

end thereof and anchored to the end walls, said inner resilient side wall being removably supported in spaced proximity to an outer side wall.

2. A container comprising end walls and outer side walls, and a liner comprising spaced resilient side wall components and a joining bottom section, said liner nesting between said outer side walls with said spaced resilient side wall components anchored to said end walls away from any contact with said outer side walls.

3. A container comprising side and end walls, each of said end walls including a reinforcing end brace, and a liner having spaced resilient wall components and a joining section, said liner nesting between said side walls with said spaced resilient wall components supported by and locked between said end braces in spaced relationship to and against lateral end movement in the direction of said side walls.

4. A container comprising end walls and outer side walls, each of said end walls including a reinforcing rectangular frame attached thereto and having a pair of upright members, and a liner means having resilient inner side wall components substantially parallel to said outer side walls, with the ends thereof extending within said frames and held by said end walls to maintain said resilient inner side wall components in spaced relationship to said outer side walls.

5. A container comprising end walls and outer side walls, each of said end walls including a reinforcing rectangular frame attached thereto and having a pair of upright members, and a pair of resilient inner side wall components extending within said frames and adapted to bear against said upright members in response to pressure of contents in said container and be held in spaced relationship to and against lateral end movement in the direction of said outer side walls.

6. A container comprising side and end walls, a liner having side wall sections and a joining section, a plurality of resilient strips affixed to said side wall sections lengthwise of said container and extending beyond the ends of said liner, said liner nesting between said side walls with the extending ends of said strips in locking engagement with said end walls to preclude lateral end movement of said side wall sections in the direction of said side walls.

7. A container comprising side and end walls, a liner having side wall sections and a joining section, a plurality of resilient strips affixed to said side wall sections lengthwise of said container and extending beyond the ends of said liner, said liner nesting between said side walls with the extending ends of said strips in locking engagement with said end walls at locations spaced from said side walls.

8. A container comprising end walls and outer side walls, a tab extension at the upper edge of each of said side walls, each of said tab extensions being foldable back upon itself, a liner nesting between said outer side walls and having inner side wall sections anchored in said end walls against lateral movement in the direction of said outer side walls, with portions of said inner side wall sections extendable between the folds of said outer side wall tab extensions.

9. A container comprising side and end walls, a tab extension at the upper edge of each of said side walls, each of said tab extensions being foldable back upon itself, a liner nesting between said side walls and having side wall sections, each side wall section including a plurality of re-

silient members affixed thereto and locking in with said end walls against lateral end movement in the direction of said side walls, with portions of said side wall sections extendable between the folds of said tab extensions.

10. A container comprising end walls and outer side walls, a tab extension at the upper edge of each of said side walls, each of said tab extensions being foldable back upon itself, a pair of resilient inner side wall components anchored in said end walls in spaced relationship to said outer side walls, with portions of said resilient inner side wall components extendable between the folds of said tab extensions.

11. A container comprising end walls and outer side walls, a tab extension at the upper edge of each of said side walls, each of said tab extensions being foldable back upon itself, a liner having a pair of inner side wall sections, resilient strips affixed to said inner side wall sections and anchored in said end walls at points spaced from said outer side walls, with portions of said inner side wall sections extendable between the folds of said tab extensions.

12. A rectangular container comprising side and end walls, each end wall including an end brace therein having spaced parallel uprights, and means for covering the interior exposed side of each of said end braces, tabs formed in each of said brace covering means adjacent said uprights, resilient wall components terminally engaging said end walls, each resilient wall component including a section of fiberboard or the like and narrow resilient strips affixed thereto and extending through each of said brace covering means past said tabs into contact with uprights in each end brace and separated thereby from an adjacent side wall, extensions formed on said side walls, double scored to permit said extensions to fold flat upon the end walls of said container, and means for maintaining said side extensions in said flat folded position.

13. A rectangular container comprising side and end walls, each end wall including an end brace therein having spaced parallel uprights, and means for covering the interior exposed side of each of said end braces, tabs formed in each of said brace covering means adjacent said uprights, resilient wall components terminally engaging said end walls and including narrow resilient strips affixed thereto and extending through each of said brace covering means past said tabs into contact with uprights in each end brace, and separated thereby from said side walls, a liner disposed between said side walls and said resilient wall components and including a bottom portion and portions extending above said resilient wall components, said bottom portion of said liner adjacent said end braces being bent up to retain said braces and said brace covering means in position, the portions of said liner extending above said resilient wall components cooperating with tab extensions from said side walls to form top portions for said container.

14. A rectangular container having sides, ends, and a bottom, end braces therein, means for covering said end braces, tabs cut through said brace covering means, auxiliary sides terminally contacting said end brace coverings and comprising liner sections fixed to narrow resilient strips extending through said cut tabs into contact with said end braces, and being separated thereby from said sides, extensions formed on said sides, double scored to permit said exten-

sions to fold flat over said container, and means for maintaining said side extensions in said flat folded position.

15. A rectangular container having sides, ends, and a bottom, end braces therein, means for covering said end braces, tabs cut through said brace covering means, auxiliary sides terminally contacting said end brace coverings and comprising liner sections fixed to narrow resilient strips extending through said cut tabs into contact with said end braces, and being separated thereby from said sides, a liner covering said bottom, disposed between said sides and said auxiliary sides and extending therebeyond, the bottom portion of said liner adjacent said end braces being bent up to retain said braces and said brace coverings in position, the portions of said liner extending beyond said auxiliary sides cooperating with extensions from said sides to form top portions for said container.

16. A container having sides, ends, and a bottom, end braces therein, extensions from said ends folding over and enclosing said end braces, a liner covering said sides and bottom between said ends, said liner having tabs cut in the portion thereof covering said bottom adjacent said end braces, said tabs being bent back to engage the end extensions covering said braces and to maintain said braces and coverings in position; auxiliary sides positioned within said container comprising liner sections covering resilient strips fixed thereto and extending through tabs cut in said end extensions whereby said strips may engage said end braces and be separated thereby from said sides; said liner extending above said sides and being folded between extensions from said sides to form top segments, said top and side portions being doubly scored at their contiguous portions, whereby the said top portions may be folded flat at varying heights relative to said bottom, and means for maintaining the position of said folded top portions.

17. In a fabricated container the combination of an outer casing having bottom, sides, and ends, and extensions on the ends adapted to be bent inwardly into a spaced position substantially parallel with the ends, a reinforcing member fitted against each of said ends and enclosed within said space, and a liner fitted to said container having bent up elements in pressure engagement with said inwardly turned extensions to secure said reinforcing members against displacement, the sides of the liner extending substantially to the ends of said container and being in side contact with said reinforcing members.

18. A container having sides, ends, and a bottom, auxiliary ends comprising liner sections having brace members attached thereto, tabs cut through said liner sections, auxiliary sides comprising liner sections fixed to narrow resilient strips extending longitudinally therebeyond, said extending strip portions being positioned to project through said cut tabs and engage said brace members, whereby said brace members may separate said auxiliary sides from the container sides, and top extensions formed on said side and end portions scored to permit bending to close said container.

19. In a container having sides, ends, and a bottom, auxiliary sides comprising liner sections fixed to resilient strips extending therebeyond and of length slightly less than the distance between said container ends, auxiliary ends fitting snugly therein, each comprising a liner section fixed to brace members having tabs cut therein,

said liner extending beyond said brace members, having the extending portions folded back upon said liner, and having additional braces secured to said folded back portions, said auxiliary sides and ends being so positioned and arranged that said resilient strips may extend through said tabs and engage said braces, said tabs retaining said

5 strips in such position and said braces separating said auxiliary sides from said container sides, top extensions from said container sides and ends separated therefrom by double scorings permitting said top extensions to be folded over said container at variable heights.

WILLIAM V. ROBERTS.
